VACUUM REGULATION FOR RECTIFIERS.

1,251,562.

Specification of Letters Patent.

Patented Jan. 1, 1918.

Application filed February 3, 1915. Serial No. 5,889.

To all whom it may concern:

Be it known that I, HAROLD A. NEWCOMB, a citizen of the United States, and a resident of Wilkinsburg, in the county of Allegheny and State of Pennsylvania, have invented a new and useful Improvement in Vacuum Regulation for Rectifiers, of which the following is a specification.

My invention relates to vacuum electric apparatus, such, for example, as mercury-vapor rectifiers, and it has for its object to provide means and methods whereby the vacuum may be readily controlled in apparatus of the character specified.

15 The single figure of the accompanying drawing is a diagrammatic view of a mercury rectifier, with attendant circuits, arranged for the practice of my invention.

The ordinary small-current mercury-vapor rectifier comprises a highly evacuated container of glass or similar material provided with a cathode of mercury or some other reconstructing conducting material and also provided with anodes, generally of 25 iron or carbon. In the operation of devices of this character, it is frequently noted that, after long service, the vacuum within the container rises to such a high degree that the rectification becomes unstable. The resistance of the vapor path reaches an abnormally high figure and eventually the arc fails from one anode. The ensuing unilateral rectification, persisting for but a single wave in a rectifier maintained by a reactance 30 coil but exhibited indefinitely when maintenance is by a direct current arc, causes an unbalanced absorption of energy from the supply system with resultant voltage surges and liability of injury to the rectifier. This

40 increase in the vacuum is apparently similar to the well known "hardening" of the vacuum in X-ray tubes. While I do not wish to be confined to any one theory for explaining this action, apparently the small current-carrying bodies and gas particles within the container are driven by the violent cathode bombardment either into or through the walls of the container. On the other hand, it frequently happens, by reason of overloads, 45 or other causes, that the anodes and walls are overheated to such an extent that they give off excessive amounts of occluded gases, and the vacuum is lowered to a point where short-circuiting is liable to occur, with con- 50 sequent extremely rapid liberation of gases;

By my invention, I am enabled to restore a proper degree of vacuum in a tube which has failed in either of these ways, so that it will give many additional hours of service.

In the accompanying drawing, 1 is the 60 container of a rectifier that is constructed of glass, quartz or similar material. Two anodes 2 and 3, constructed preferably of carbon or iron, are mounted in laterally extending arms at a considerable distance 65 from each other in order to prevent short circuiting. A cathode 4 of mercury or other suitable conducting self-reconstructing material is placed in the lower portion of the container 1.

70 In the normal operation of a rectifier of this character, the current flows alternately from the anodes 2 and 3 to the cathode 4 until the vacuum reaches such a high point that the arc becomes unstable. Under these 75 conditions, by my invention, I first heat the cathode 4 by any suitable external means, such, for example, as a Bunsen burner 5, sufficiently to vaporize a small portion of the mercury. By means of an adjustable high- 80 potential transformer 6, a high-potential discharge of considerable amperage is then caused to flow between the anodes 2 and 3 and through the current-conducting bodies evolved from the cathode. The high-potential 85 electric discharge between the anodes 2 and 3 causes intense local heating thereof and serves to set free occluded gases therefrom; thus lowering the vacuum to such a point that the rectifier may be restored to 90 normal operation.

On the other hand, the vacuum in a bulb sometimes falls because the rate of gas liberation from the walls and anodes exceeds the normal rate of gas suppression. This is generally due to overloading or to improper treating-out in the manufacture of the bulb. I then proceed as in the previous case, heating the cathode pool with an external source of heat in order to form a conducting bridge 100 between the anodes but I pass a high-tension current of very low amperage between the anodes. By employing a sufficiently small current, the heating effect on the anodes is minimized and gas liberation therefrom is 105 substantially prevented and, at the same time, I obtain an effective gas suppressing or dispelling action by reason of which the vacuum is soon restored to normal.

The time during which the gas-control- 110

ling arc is applied to the bulb is also an important factor. Generally speaking, the heavy-current discharge for vacuum reduction should be applied for but a short time, 5 whereas the small-current discharge for vacuum raising should be maintained for a considerable period. With some tubes, in order to obtain gas-suppressing action, it is necessary to use current of such amount that 10 the heating of the anodes approaches the gas-liberating point and it is then necessary to desist until the anodes have cooled. Furthermore, under certain conditions, I find that, with a given current, there may be first 15 a lowering of the vacuum and then a raising thereof. This action is apparently due to the fact that gases are first given off by the portions of the anodes most directly exposed to the action of the discharge and 20 this gas is subsequently absorbed by the portions of the anodes which are less subject to the action of the discharge. By careful control of the time of discharge, therefore, it is possible to obtain nearly any degree 25 of vacuum.

I am aware that attempts have been made in the past to evolve gases from the electrodes of a rectifier by means of an extremely high-potential electrical discharge. 30 My invention differs from this practice essentially in the fact that I employ a conducting bridge of material vaporized from the cathode for conveying the current from one electrode to the other. In the past, extremely 35 high potentials have been impressed upon the defective bulb for the purpose of breaking down a current path through the impaired vacuum. This is a dangerous practice as it is liable to puncture the tube.

40 I have found that sufficient mercury particles can be driven off from the cathode by external heating to provide a satisfactory current bridge and still not affect the gas pressure to a harmful degree. The mercury 45 may be considered as an inert substance superposed upon the gases within the container and merely performing the function of a temporary current carrier.

Frequently, the potential gradient is so 50 steep near one of the anodes, as to cause the puncture of the container wall. I find that, by connecting the cathode 4 to the mid point 55 of the secondary winding of the transformer through a high-resistance member 8, the potential strains within the container are distributed and puncture is avoided.

In this specification and claims I am not 60 using the term "vacuum" in its strict, absolute, physical meaning but rather in the relative sense commonly employed in this art. Thus, to raise the vacuum implies merely exhaustion, and to lower the vacuum implies gas charging from any source whatever. I

have described my invention in its preferred form, but it is obvious to those skilled in the art that it is susceptible of many changes and modifications, in degree and in manipulation, without departing from the spirit thereof. I desire therefore that no limitations shall be imposed except such as are set forth in the appended claims or are imposed by the prior art.

I claim as my invention:

1. The method of aiding current flow between two electrodes within an evacuated 7 container which comprises applying heat to an inactive pool of vaporizable material within said container.

2. The method of producing current flow between two anodes of a multi-anode vapor 8 converter which comprises connecting a source of electromotive force between said anodes and heating the cathode without breaking down the negative-electrode reluctance thereof.

3. The method of producing a vacuum-regulating flow of current within a multi-anode vapor-arc converter which comprises connecting a source of electromotive force across two anodes thereof and applying heat 9 to the cathode.

4. The method of regulating the vacuum in a vapor-arc converter which comprises producing a conducting vapor bridge therein between two electrodes which are inactive 9 with respect to each other during normal operation, and connecting a source of electromotive force therebetween, whereby a vacuum-regulating current is caused to flow.

5. The method of regulating the vacuum 1 in a vapor-arc device which comprises producing a flow of current between two electrodes thereof, and adjusting the amount of said current flow by supplying carriers to the arc path from a source which is adjustable independent of the current flowing in said arc.

6. The method of raising the vacuum in a multi-anode vapor converter which comprises producing a current flow between two 1 anodes thereof of sufficiently high voltage and small amperage to cause the elimination of gas particles from the arc space at a faster rate than they are evolved from the electrodes, and adjusting the amount of current 1 in said arc by supplying the arc path with carriers from an independently adjustable source.

In testimony whereof, I have hereunto subscribed my name this 29th day of January, 1915.

HAROLD A. NEWCOMB.
